ELECTRIC HEATER UNIT

Samuel Dowinsky, New York, N. Y.

Application May 23, 1934, Serial No. 727,036
Renewed December 14, 1935

3 Claims. (Cl. 219—25)

This invention relates to the windings of electrical heater units, and particularly to devices adapted to be used in the heating of smoothing irons.

5 One of the objects of the invention is to provide a thin, flat heating element, readily portable and of light weight, on which the iron may be placed while receiving the desired thermal effect, or which may be built into the iron as a 10 component, integral part.

A further feature is in the provision of means 15 to control the degree of heat it is desired to impart selectively, by mechanically arranging the resistance coils into different groups of varying watts or volt-amperage, all of which are in the same level plane.

Another purpose is to produce a heating element of unusual thinness, strength, durability and economical construction.

20 These desirable objects are attained by the novel construction, arrangement and combination of parts hereinafter described and shown in the accompanying drawing, constituting a material part of this disclosure, and in which:

25 Figure 1 is a top plan view of an embodiment of the invention.

Figure 2 is a similar view of a modified form of the same.

Figure 3 is a sectional view taken on line 3—3 30 of Figure 1.

The core-like, plate body 15, of the device may be any thin flat dielectric material, preferably mica, because it is non-absorbent to moisture in the atmosphere, not affected by heat, nor does 35 it readily crack, crumble or disintegrate.

The plate 15 may be solid or laminated, its profile shaped in conformity with its purpose, here shown as adapted for use in heating a smoothing iron, but obviously can be made of 40 any desired configuration.

The plate 15, as shown in Figure 1, is provided with apertures 16—17 through which may pass securing means whereby it is properly anchored, the larger apertures 17 also permitting the passage of steam, if it be used in connection with the iron.

In the opposite side edges of the plate, near 50 its wider, heel portion, are a group of rectangular notches 18—18' in its respective edges, uniformly spaced apart, the notches being substantially equal in width to the spaces therebetween, beyond which are a lesser number of similar, but more widely spaced notches 19—19', and further 55 out are another uniform series of notches

20—20', while therebeyond, reaching almost to the point, is the final series 21—21'.

In the heel portion of the plate 15, spaced inwardly from the notches 18—18' on both sides, are a corresponding series of square perforations 5 38—38', similar openings 39—39' registering with the notches 19—19', and further towards the point is another series of perforations 40—40', corresponding to the notches 20.

Spaced laterally adjacent the larger aperture 10 17, on each side, are similar perforations 41—41' arranged in arcuate formation, and at their apex is a central longitudinal row 41''.

At the rear of the plate 15, in the right side thereof as shown, is an opening 22, while further 15 to the right is a second opening 23, and still further to the right is a third opening 24, these several openings being in alignment and adjacent the rear edge of the plate.

At the left hand side is an opening 25, while 20 to the right are two contiguous openings, respectively 26 and 27, these last named openings registering with the first of the series of openings 38; thereabove is a single opening 28 registering with the sixth opening 38f of the outer row of 25 perforations 38, while adjacent the right hand side of the central circular aperture 16 are a plurality of similar openings 29, arranged in a longitudinal row, intermediate the aperture 16, and small openings 29, is an opening 30, registering with the third opening 39c in the row 39, and rearward of the opening 30, in the plate 15, is another opening 31.

On the opposite side of the aperture 16 are a series of openings 32 corresponding to the openings 29, all of these several openings being rectangular and of a size commensurate with their purpose, which is to receive the resistance wire.

A flat strip of wire of high electrical resistance material, having an end 42 for connection to a 40 source of electrical energy, is passed down through the opening 22, up out of the opening 23, along the upper surface of the plate 15, into the opening 24, and out at the first peripheral notch of the series 18 on the right hand side, then 45 passed through the corresponding first perforation in the series 38, on the right hand side, and wound thereafter alternately up and down through the notches and perforations 18—38, 19—39, 20—40, 21—41, and 41'', returning on the 50 opposite side in the same manner, finally threaded up through the opening 27 to constitute a tap end 43, thus constituting the first and longest coil in the series.

Passing down through the same opening 27 is 55

another resistance wire, having an inner tap end 44 directed upwardly through the opening 26 and the wire extending thence across the plate 15, through the second opening in the row 38' and 5 then wound alternately through the openings 38—38' to emerge through the opening 38f to form a tap end 45, this coil constituting the second and shortest coil in the series.

In a similar manner another resistance wire 10 having a tap end 46 is passed down through the opening 38f, then up through the opening 28 to the first opening in the row 29, thereafter alternately up and down through the openings 29—39 15 to 39d, thence down through 30, bent rearwardly towards the heel, to pass up through 31 to the opposite side of the plate, where it is passed alternately through the openings 32 and 39' on the left hand side and continued through a part 20 of the adjacent rows of openings 39—39' to extend upward through the opening 40c to form a tap end 47, this winding constituting the third coil in the series.

Another resistance wire having a tap end 48 passes down through the opening 40c, thereafter 25 to be wound through the row of openings 40—40' to the last one 49m in the series, from which it extends to form a tap end 49, constituting the fourth and last coil in the series.

It will be understood that the resistance wires 30 may differ in the several coils in cross sectional area and, hence potential resistance to the current passing through them, and it will also be understood that contact buttons, not shown, are provided at the paired taps 43—44, 45—46, 47—48, 35 and single tap 49.

A switch arm, not shown, pivoted at the point 50, is connected with the other pole of the electric circuit and is capable, as indicated by the radial lines, of swinging in the arc of a circle to selectively engage the tap buttons whereby any of the 40 several resistance coils may be placed in circuit.

For instance, in the device shown in Figure 1, when the shortest circuit, between the switch arm and tap end 44 is completed, approximately 660 45 watts is obtained; when the switch arm is moved to engage the tap end 46, the wattage is decreased to 530 watts; when in contact with the tap end 47 there is a further decrease to 400 watts; and when engaged with the single tap 49, the lowest 50 degree of heat 280 watts is imparted, this, the longest circuit, enclosing within its interior profile all of the several shorter circuits in the manner indicated.

The windings of the resistance wire as seen in

Figure 2, are of a similar type, the heating capacity being controlled by a switch arm centered at 60 and operative to engage taps 61—62; 63—64; 65—66; and 67, current passing from the switch arm centered at 68, to the various taps 5 and entering at the terminal 69.

Having thus described the invention and set forth the manner of the construction and operation of its best known embodiments, what is claimed as new and sought to secure by Letters 10 Patent, is:—

1. A heating unit comprising a dielectric plate having spaced notches in its marginal edge and having spaced perforations therein aligned with and spaced inwardly from said notches respectively, a resistance wire passed around said plate and extending in said notches and perforations to form a helix overlying that portion of the plate between the perforations and the edge of the plate, and a second resistance wire passed around 15 said plate and extending in said perforations to form another helix overlying that portion of the plate between the perforations, said helixes being electrically connected to each other and being of different current capacities. 25

2. A heating unit comprising a dielectric plate, a resistance wire engaged with said plate to provide a flat helix extending about opposite side marginal portions of the plate, and a second resistance wire engaged with said plate to provide 30 another flat helix extending about the plate between said first helix, one terminal of one helix being connected with one terminal of the other helix, and said helixes being of different lengths. 35

3. A heating unit comprising a dielectric plate 40 having spaced notches in its edge at opposite sides thereof, and also having spaced perforations therein spaced inwardly from said notches, said perforations being arranged in groups offset with respect to each other, a resistance wire passed around said plate and extending in said notches and perforations to form a helix overlying that portion of the plate between the perforations and the edge of the plate at opposite sides thereof, and additional resistance wires passed around 45 said plate and extending in said perforations to form additional helixes overlying that portion of the plate between the perforations, said helixes being electrically connected to each other in series, and certain terminals of said helixes projecting upwardly through certain of said perforations. 50

SAMUEL DOWINSKY.
